HUGO LENTZ, OF BERLIN-HALENSEE, GERMANY.

VALVE.

1,133,650.

Specification of Letters Patent. Patented Mar. 30, 1915.

Application filed January 20, 1915. Serial No. 3,354.

To all whom it may concern:

Be it known that I, HUGO LENTZ, a citizen of the German Empire, and resident of Berlin-Halensee, Germany, have invented certain new and useful Improvements in Valves, of which the following is a specification.

My invention relates to improvements in valves, and more particularly in valves of that class, in which the inlet and outlet passages adjoining the valve gate or plug are in the form of funnels so as to provide a nozzle, and in which the cross-sectional area of the inlet nozzle is smaller than the adjacent cross-sectional area of the outlet nozzle, so that within the chamber which receives the valve gate a vacuum is produced.

One of the objects of the improvements is to provide a valve of this class, in which a small stroke of the valve gate is sufficient for opening the same, and in which the suction is comparatively large from the beginning of the opening movement of the valve gate. With this object in view my invention provides for constructing the inlet and outlet passages of the valve at the ends which are adjacent to the gate with elongated cross-sections. In the preferred form of the valve the elongated cross-sections of the inlet and outlet passages are so arranged relatively to each other, that they are disposed with the walls opposite to the controlling edge of the gate in line with each other. By thus constructing the valve the larger part of the area of the passages comes into action for producing the vacuum as soon as the valve gate is moved into opening position and when a small part of the passage is laid open.

My improved construction is further preferable as compared to constructions in which the valve gate is provided with a circular opening, because the chamber for receiving the valve gate can be disposed transversely of the valve casing and it can be closed at opposite sides of the casing by means of simple caps, because by reason of the vacuum produced within the valve casing simple tightening means for the said caps are sufficient.

Finally an important advantage of my improved construction resides in the fact, that the size of the valve casing is comparatively small, and that the chamber receiving the valve plug or gate can be made in a single operation by *fraising*.

For the purpose of explaining the invention an example embodying the same has been shown in the accompanying drawing, in which the same letters of reference have been used in all the views to indicate corresponding parts.

In said drawing—Figure 1, is a vertical longitudinal section of the valve, showing the gate or valve in closing position, and Fig. 2, is a vertical cross-section taken on the line 2—2 of Fig. 1.

In the example illustrated in the drawing the valve consists of a casing *a* which comprises an inlet passage *b* and an outlet passage *c* which are separated from each other by a chamber *d* disposed transversely of the casing and extending from one side thereof to the other. In the manufacture of the casing I prefer to make the chamber *d* when casting the casing and to fashion the same afterward by *fraising*. At the side of the inlet passage *b* of the casing a tightening plate *g* of suitable hard or tempered metal is fitted in the side wall of the chamber *d*. The said plate can be constructed in such a way that it can easily be replaced by another plate, or if desired it can be cast together with the casing. The said plate provides a nozzle part for the inlet passage *b* which is not subject to wear. At its opposite ends the chamber *d* is closed by caps or lids *h* and *i*, the construction being such that the said caps also hold the tightening plate *g* in position and to tighten the same at its ends. The caps *h* and *i* are secured to the valve casing by screws *k*.

The cross-sections of the inlet and outlet passages *b* and *c* are circular at their outer sides at *b'* and *c'* respectively and gradually merge into elongated or substantially rectilinear sections *b''* and *c''* at the ends which are adjacent to the plug chamber *d*, the longitudinal axes of the said elongated portions being transverse of the direction of the movement of the gate. The upper walls of the elongated portions of the inlet and outlet passages are located so as to register with each other, and the other walls of the outlet passage are located at a distance laterally and downward from the corresponding walls of the inlet passage, so that the fluid rushing through the elongated part of the outlet passage has the function of a jet of fluid flowing through an injector, and thereby causes a partial vacuum within the chamber *d*. Thereby outward pressure at

the joints is decreased and this makes it practicable to close the casing at both sides of the chamber *d* by simple caps *h* and *i*.

Within the chamber *d* the valve gate is located which as shown consists of two steel plates *e* and *f* formed at their adjacent sides with cavities receiving a roller *l*. The upper wall of the cavity of the plate *f* is beveled at one side, so that when shifting the said plate downward relatively to the plate *e* the plates *e* and *f* are forced apart. Between a flange *f'* of the plate *f* and the top of the plate *e* a spring *m* is interposed which tends to shift the plate *f* upward relatively to the plate *e*, so that the roller *l* and beveled bottom wall of the cavity of the plate *f* are inoperative. When shifting the valve gate formed by the plates *e* and *f* downward the roller is at first inoperative by reason of the action of the spring *m*, but near the end of the downward stroke of the gate the plate *e* strikes an upwardly directed flange of an angular stop member *n* so as to be arrested thereby, while the plate *f* is moved farther downward, and the roller *l* comes into operation so as to ride on the beveled bottom of the cavity of the plate *f* and force the latter outward. Thereby the plate *e* is forced in tight contact with the plate *g*. When opening the valve gate, the plate *f* is at first moved independently of the plate *e* so that the gate is loosened by the action of the roller *l*, and thereafter the plate *f* engages with a nose *f²* below a shoulder *e²* formed on the plate *e*, so that the plate *e* is carried along. By thus constructing the valve gate *e*, *f* a tight joint is produced on the plate *g* and yet the gate can easily be moved for opening or closing the valve. For moving the gate in the manner described a screw-threaded spindle *o* is provided which engages with a flange *o'* formed at its lower end in a housing *f³* formed at the top of the plate *f*, and which is passed through a nut *r* formed with a flange *r'* and fitted in the upper cap *i* where it is held in position by a plate *i²*. The nut *r* carries a hand wheel *p* for rotating the same, and when thus rotated the nut shifts the gate *e*, *f* upward or downward. The flange *r'* is formed with annular grooves *s* providing a tight joint between the flange and the walls of the cap *i* and plate *i²*.

As appears from Fig. 1, the valve and its casing are not larger than the usual flanges *b³* and *c³* by means of which the casing is secured to the pipes, so that it can be covered by the same sheet metal jacket *u* as the said pipes. Besides it can be taken apart by loosening the screws *k*, so that access can be had to all the parts.

I claim herein as my invention:

1. In a valve for high pressure gaseous fluid, the combination of a casing having an inlet and an outlet passage with an inter-

mediate valve gate for closing communication between the two passages, said inlet passage gradually tapering down to a nozzle opening of elongated and materially reduced cross section at the gate, narrow in the direction of movement of the gate to form a nozzle to increase the velocity of the fluid at the gate, and the outlet passage being of greater cross sectional area at the gate than the elongated nozzle opening, whereby the flow of the high velocity fluid tends to create a vacuum at the gate to prevent leakage thereat.

2. In a valve for high pressure gaseous fluid, the combination of a casing having an inlet and an outlet passage with an intermediate valve gate for closing communication between the two passages, said inlet passage being circular in cross section and gradually tapering down to a nozzle opening of elongated and greatly reduced cross section at the gate, narrow in the direction of movement of the gate to form an elongated nozzle to increase the velocity of the fluid at the gate, and the adjacent end of the outlet passage being of greater cross section than the nozzle section and having its wall adjacent the controlling edge of the gate extending beyond the corresponding wall of the nozzle opening, whereby a reduction in pressure at the gate is caused by the flow of the high velocity fluid when the gate is partially open.

3. In a valve for high velocity gaseous fluid, the combination of a casing having an inlet and an outlet passage with an intermediate valve gate for closing communication between the two passages, said passages each being of elongated cross section at their adjacent ends and narrow in the direction of movement of the gate and each flaring outwardly with gradually and materially increasing cross section, the inner end of the outlet passage being of greater cross section than the adjacent end of the inlet passage whereby the gaseous fluid is delivered with increased velocity at the gate where it is permitted to suddenly expand so as to tend to produce suction.

4. In a valve for high velocity gaseous fluid, the combination of a casing having an inlet and an outlet passage with an intermediate chamber and a valve gate in the chamber for closing communication between the two passages, said passages each being of elongated cross section at their adjacent ends and narrow in the direction of movement of the gate and each flaring outwardly with gradually and materially increasing cross section, the inner end of the outlet passage being of greater cross section than the adjacent end of the inlet passage and having its wall adjacent the controlling edge of the gate extending beyond the inner end of the corresponding wall of the inlet open-

ing, whereby the inlet passage will act as a nozzle to increase the velocity of the fluid as delivered at the gate and whereupon the fluid is permitted to expand behind the gate 5 so as to produce a partial vacuum.

5. In a valve for high velocity gaseous fluid, the combination of a casing having a gate chamber, a gate movable therein, and inlet and outlet passages arranged trans- 10 versely thereof and communicating therewith, said passages being circular in cross section at their outer ends and gradually and materially reduced in cross sectional area from their outer ends toward said 15 chamber where they are elongated in section, being narrow in the direction of movement of the gate, the sectional area of the gate chamber below the gate when in its full open position, and the cross sectional area 20 of the outlet passage adjacent the chamber each being greater than the cross section of the adjacent end of the inlet passage, whereby the inlet passage acts as a nozzle to increase the velocity of fluid delivered at the 25 gate and the flow of fluid at high velocity

past the gate produces a reduction in pressure in the gate chamber to prevent leakage.

6. In a valve, the combination of a casing substantially circular in cross section at its outer ends and tapering inwardly toward 30 the center on at least two sides to a substantially rectangular sectional form, a chamber in the rectangular part of the casing having a substantially rectangular opening at two opposite sides, and inlet and outlet passages communicating with the chamber and flaring outwardly therefrom to gradually increased cross section, a gate in the chamber, caps closing the rectangular openings at the sides of the chamber, and 35 means extending through one of the caps for moving the gate.

In testimony whereof, I have signed this specification in the presence of two subscribing witnesses.

HUGO LENTZ.
